R. P. Cunningham,

Cheese Press.

Patented May 21, 1808.

Robert Peacock Esq Esq Esq Esq

London

The schedule is made to an elevoty, Talbot and making
part of the same, containing a description in the words of
the said Robert Peacock- Cunningham himself of his machine
for hoisting.

This pump consists of the frame, the wheel, arms, and axis
the thuster connected with the axis and the pump or lever.
The frame of this pump may be made of metal or wood, as the user
to which it is applied shall dictate to be best, and its form will
vary accordingly; so as to exclude unnecessary any particular speci-
fication thereof. The wheel or arms by which motion may be com-
municated will also be various, it may be either a wheel in the
size of a wheel barrow a cap or a chain for the purpose of sustai-
ning a weight adequate to give the pressure; or a wheel which
which is turned by a crank or pinion as in the common jacks, or
loaded arms, or a lever, the arms or spoke of the wheel may
help through perforating of the axis if the user should be of such
as they may be fixed in mortises in the axis; or the wheel and axis
may be of one substance cast or framed together. These things
depending on the opinion of the contractor, or the purpose for
which the pump is intended. The arms of these wheels, and the
axis the thuster, however specified or else on one end
thereof a cylindrical barrel round which winds a rope or
chain the string back the barrel so firm, after the pump
is prepared, or if necessary two ropes, or chain, one on each
side the thuster, this barrel is of any diameter which the
contractor chooses, greater or less than that of the axis, and the pump
to be applied; or other circumstances which determine. The thuster

on which the weight of this machine shall rest, which I have called
simply as my invention, is a tooth or spur similar to the one above
mentioned, and of a spiral figure which shall drive the presser
and bear upon it with an equal force in every situation. It may
either make whole oscillations, or a part only of a oscillation accord-
ing to the instance the presser has to be moved. The form is such
that it drives the presser in a direct line with a constant &
uniform force; and may be thus described or delineated.

First draw a circle of the diameter of the barrel round
which the rope or chain coils. that brings back the barrel of
the press after the presser is affected. then draw the line of a
diameter of that circle to intersect the periphery of a concentric
circle, whose diameter is equal to the axis of the wheel a tan-
gent drawn from this point to intersect another tangent drawn from
the end of one of the radii of the barrel which shall be perpen-
dicular to the diameter first drawn, will give a point at which
the spiral commences, the part within the line of the tangent just
mentioned forming part of the tooth. Then draw as many tangents
to the barrel as may be thought necessary, and upon them lay
off a distance equal to the radius of the axis of the wheel, added
to that part of the periphery of the barrel which is between the
end of the perpendicular radius above mentioned and the point in
the periphery from which the tangent is drawn. The point thus
found will be those through which will pass the spiral curve of the
thrustor. Allowance must be made in ascertaining the curve of the
thrustor, for the thickness of the rope or chain which winds round
the barrel; this allowance cannot be particularly specified as
it will depend on circumstance. The thrustor may be made of
any proper substance as hard wood, or metal. The presser, or
beam, or tongue of the press is a straight beam against one end
of which the thrustor acts and propelled forward. A horizon
wheel may be placed at the end of this beam, which is acted
upon by the thrustor the point of contact of the thrustor and

22

friction wheel being in the line of the motion of the beam or frame and the axis of the friction wheel. The edge or outer parameter of this friction wheel which is acted upon by the thruster will be left rounded so as to approach the form of the middle prismatic of a spire, or indented together with the cam or thruster, in this case the moving power may be applied to the friction wheel and produce an increasing pressure.

I contemplate applying this press to all cases where a great force and constant pressure is required and where the distance through which the press or tongue passes is not large as in the pressures for cheese, soap, &c. for Stock Biscuit Biscuits, Dye, Paint, &c. and the pressure upon drily and in mechanical operations, or it may be used for moving heavy bodies a small distance either by the thruster or a wheel and axis or both in the same.
